GAS ANALYZING PROCESS AND APPARATUS

John D. Morgan, South Orange, N. J., assignor
to Doherty Research Company, New York,
N. Y., a corporation of Delaware

Application March 14, 1932 Serial No. 598,607

15 Claims. (Cl. 236—15)

This invention relates to combustion control and more especially it relates to a method and apparatus for rapidly and accurately controlling the supply to a combustion zone of one or 5 more elements of combustion. It has special utility in the control of combustion in an internal combustion engine of the automotive type, although it is adapted for use in the various types of heating, and heat-treating furnaces when operated either over-ventilated or under-ventilated.

It has long been known that a diffusion cell made up of two chambers separated by a porous gas pervious wall can be used for indicating the presence in the air of mines of a small amount 15 of certain gases such as fire damp or gas damp. When thus used, one of the chambers, after being filled with air, is placed in the mine at the point where the air is to be tested. It is now known that the rate of diffusion of a gas through 20 a porous diaphragm at a given temperature and pressure is inversely proportional to the square root of the density of such gas. Therefore the lighter gases in the mixture will penetrate through the porous wall in one direction more 25 readily than the heavier gases flow in the opposite direction through the wall, resulting in an increase in pressure in one chamber, which may be measured directly or may be employed for giving a suitable warning signal. The diffusion 30 in apparatus of this type heretofore known has been slow and the rate of pressure increase therein has been low, making it unsatisfactory for the determination of combustion efficiencies where quick determinations are necessary in order to 35 permit prompt adjustment of the air and fuel flowing to the combustion zone. Furthermore it required manual operation, and great care was needed if comparable results were desired, since the time of exposure of the fluid to the dia- 40 phragm is an important element.

The gases normally formed in combustion operations contain varying mixtures of carbon monoxide, carbon dioxide, hydrogen, methane, nitrogen, oxygen, and sometimes other hydrocar- 45 bons in small amounts. For instance, in the exhaust gases flowing from an internal combustion engine of the automotive type, the percentages of the above gases therein vary about as follows:

50 Carbon dioxide.....	5.7% to 13.4%
CO.....	13% to 1.2%
Oxygen.....	1.1% 1.1%
Hydrogen.....	7% to 1.2%
55 Nitrogen.....	71.5% to 84%
CH ₄	1.7% to .1%

The first and second values given for each gas are those found in the exhaust gases from operations at 50% and 95% combustion efficiency 60 respectively. The relative rates of diffusion of

these gaseous components through a porous dia- phragm are as follows:

Hydrogen.....	1
Carbon dioxide.....	.212
Carbon monoxide.....	.267
Nitrogen.....	.267
CH ₄	.354
Oxygen.....	.250

Prior to the present invention, therefore, a determination of the amount of reducing gases in air required considerable time with the result that such methods were not adapted for the continuous control of an element of combustion flowing to a combustion operation. Applicant 75 has now succeeded in devising a method and an apparatus operating upon the diffusion principle for obtaining rapid indications of the amount of reducing gases present in a combustion gas mixture containing a number of different reduc- 80 ing gases, and he has likewise adapted apparatus of this type for continuously controlling the efficiency of a combustion operation.

According to the present invention a sample of the gases from a combustion operation is 85 continuously withdrawn from a motor exhaust or a furnace and, after being suitably filtered and cooled to a uniform preselected temperature, and preferably stripped of any condensed moisture, is passed into a compartment of a diffusion cell that is separated from another compartment of the cell by a porous diaphragm of suitable composition such as a mixture of asbestos and steatite molded and fired to the point of vitrification. The diaphragm and associated 90 parts are so designed that there is relatively a very large diaphragm surface through which the diffusion may occur; while at the same time the space into which the reducing gases diffuse through the diaphragm is very small, so that a 100 very rapid diffusion of gases into a small space is facilitated. In this manner, a rapid increase of pressure is developed within the interior space upon passing gases containing light reducing constituents along the opposite face of the dia- 105 phragm. This pressure then acts upon a suitable manometer or equivalent device by which it is possible, after suitable calibration, to measure the change in pressure developed within the second or inner chamber in terms of the percentage of reducing gases or combustible constituents in the combustion gases being examined.

A scale may be associated with or mounted 110 on the manometer to indicate the amount of reducing gases in the combustion gases in terms of combustion efficiency of the operation producing them. When gasoline or like liquid fuel is combusted in an internal combustion engine 115

of the automotive type the scale may be made in accordance with the following table:

	Percent reducing gases	Percent of combustion efficiency
10	0	100
	1.4	93
	2.4	90
	3.1	87
	5.6	84
	16.5	65
	22.2	49

15 By suitable arrangements of parts, hereinafter described, the diffusion apparatus is operated intermittently at regular intervals of time and may be adjusted for varying the time interval as desired. Similarly provisions are made for automatically and periodically adjusting the flow of fuel and/or air to the combustion operation at frequent intervals, in accordance with the pressure existing within the diffusion apparatus at regular intervals synchronized with respect to the flow of combustion gases to the diffusion cell. Such fuel or air adjustments are then maintained until the next adjustment is effected at the end of the succeeding diffusion period. Between each diffusion measurement the inner pressure-building chamber is purged with air or other gas selected as the standard.

By the proper design of diffusion cell so as to obtain as nearly as practicable a maximum of diaphragm surface and a minimum of space in the inner pressure compartment, these successive determinations may be completed and furnace condition adjustments made in periods as short as 30 seconds or one minute.

In the accompanying drawing illustrating more or less diagrammatically apparatus adapted for the practice of the process, Fig. 1 is a somewhat diagrammatic showing of one form of such an apparatus assembly, parts being broken away;

45 Fig. 2 is a horizontal section through the diffusion cell of Fig. 1 taken along the lines 2—2 thereof;

Fig. 3 is a somewhat diagrammatic showing of one form of apparatus for fuel and air control;

50 Fig. 4 shows in vertical section another form of diffusion cell and interassociated parts, portions being broken away;

Fig. 5 is a view taken along the line 5—5 of Fig. 4; and

55 Fig. 6 is a horizontal section taken along the line 6—6 of Fig. 4.

Referring now to Fig. 1, numeral 10 designates a furnace provided with a fluid fuel inlet 12 and an air inlet 14, the latter being connected through 60 suitable piping with the fan 16 driven by a variable speed motor 18.

For removing from the combustion zone a sample of gas to be examined and for preparing it for the diffusion operation, there is provided 65 a combustion gas offtake 20 leading from the furnace to a dry filter and drip trap 22, the latter of which may be filled with suitable filtering substance such as glass, steel wool or cotton. From vessel 22 a conduit 24 conducts the filtered gases 70 through water-cooled condenser 26 and thence to a rotary valve 28, operated by a motor or the like (not shown) through suitable gearing adjusted to effect a complete rotation of an inner member 30 of the valve in a preselected time, which may be 75 adjusted in accordance with the nature of the

gases being examined but will generally range from one to one and one-half minutes and upward.

For the purpose of effecting the separation and isolation of different components of the gas mixture in accordance with their specific gravities, there is provided a cell or chamber 32 connected with the valve 28 through the conduits 34 and 36. A conduit 38 connects the valve 28 with an aspirator 40, adapted to function under the effect of water discharged through the nozzle 42 direct from a source of supply under pressure through line 44,—or the water employed in condenser 26 may be utilized. The aspirator is provided with the usual outlet 46.

Valve 28 has provided therein a pair of passageways so constructed that the respective pairs of lines 24 and 34, and the lines 36 and 38 successively may be interconnected therethrough.

Mounted within the cell or chamber 32 is an annular porous diaphragm 48 separating the space within the cell into a pair of chambers including an outer chamber 50. The diaphragm is of such shape as to have as large as practicable an area of exposure to the gases flowing through chamber 50. In the form shown this diaphragm is star-shaped. A filler member 54, preferably hollow, is provided within the porous member 48, with its side walls spaced close to the inner walls of the latter, defining with these walls a narrow irregularly shaped inner chamber 56. The diaphragm 48 and member 54 may be corrugated to increase the surface for diffusion. The member 54 is made of gas-impermeable material such as metal or its equivalent.

The diaphragm 48 and member 54 are mounted on a base 58 in such manner as to prevent flow of gases between chambers 50 and 56, excepting through the diaphragm. A flat top portion or member 60 serves a similar purpose.

The chamber 56 is in communication at its top with a central tubular member 62 which extends upwardly through the filler member 54. This tubular member 62 extends through the base 58 of the cell and is then curved to form a leg of manometer tube 64 of small diameter as shown.

The lower part of the chamber 56 is provided with valved outlet lines 66 for the periodic release of any pressure developed therein and for the purging of the chamber. Preferably the outlet lines 66 are provided with valves operating in synchronism with the valve 28 whereby at that point in the path of travel of the inner valve member 30 immediately following the point reached when the combustion control device 130 hereinafter described is actuated, the pressure in chamber 56 is released through the lines 66.

For this purpose the lines 66 lead to an automatic valve or valves 67 leading to waste, the said valves being operated in synchronism with the valves 30 through cams 73. A conduit connected with a source of air or other gas under pressure is connected with the upper part of the chamber 56 through a conduit 69 controlled by a valve 71 operated in synchronism with the valve 30 through cam 75.

The leg of the manometer 64 outside of the cell 32 is open-ended and is provided with a plurality of vertically-spaced pairs of electric contact members, here respectively designated 68, 70, 72, 74 and 76. Within the manometer is a body of a non-conducting liquid such as light hydrocarbon oil or other suitable organic fluid, above the surface of which a member 78 is adapted to float. This float member is provided with suitable con-

ducting material such as platinum foil for the purpose of establishing an electric circuit through each contact of the respective pairs when moved into suitable position by the liquid upon which it floats.

For feeding fluid fuel such as oil or gas to the furnace 10 there is provided a plurality of valves, including one manually adjustable valve 80 which is adapted to feed a continuous supply of fuel to the furnace from fuel header 82 at all times when in operation. There are likewise provided the respective solenoid-operated valves 84 and 86 having openings of different sizes, each of the valves 84 and 86 being under the control of respective pairs of solenoids 88 and 90, in an electric circuit which comprises a battery or other source of constant electric potential 92 and the various pairs of contacts 70, 72, 74 and 76. The arrangement is such that the solenoids 88, when actuated, act to move the valves associated therewith in the opposite direction to that in which they are moved by the solenoids 90 when the latter are actuated.

The lowermost pair of contacts 68 is in circuit with a solenoid 98 adapted to adjust the flow of current through the three-phase circuit for operating variable speed motor 18. The arrangement is such that upon the completion of the circuit through the pair of contacts 68, the solenoid 98 is actuated in well-known manner to increase the speed of the motor 18 above the normal rate and thus supply more air to the furnace.

For synchronizing the operation of the diffusion apparatus with the device controlling the flow of fuel and air to the furnace so as to make the latter responsive to conditions in the former at the moment immediately prior to the time at which the pressure built up in the inner pressure chamber 56 by diffusion thereto is released,— the valve 28 is provided with a pair of electric contact members 100 adapted to be periodically interconnected through a conductor 102 mounted in the rotary member 30 of the valve. These elements 100 form part of an electric circuit comprising wires 104, 106 and the source of electric current 92. The arrangement is such that just prior to the moment at which the pressure that has been built up in the chamber 56 is released through lines 66, the electric circuit containing the various solenoids is momentarily closed and one of the solenoids is energized to adjust the fuel or air flow to the furnace.

Fig. 3 illustrates another form of mechanism adapted for energizing the various solenoids shown in Fig. 1. According to this modification, the free end of the manometer tube 64 is associated with a pressure-operated regulating apparatus 110 of well-known construction, having mounted therein a flexible diaphragm 112 of suitable material. The diaphragm 112 is operatively connected with a reciprocating member 114 through the lever member 116 and link 118. The lever 116 is fulcrumed as at 120 and is counterbalanced so that a minimum of pressure is required beneath the diaphragm for actuating the member 114. The last-named member is movable in guides 122 and has secured to it at spaced points slotted socket members 124, each adapted to house one end of respective levers 126, the other end of each lever being connected with one of a pair of pivoted "mercoid" liquid-operated switches 128. The construction of this apparatus is such that when atmospheric pressure exists in the legs of the manometer 64, the respective switches 128 are horizontally disposed but that

as the pressure in the manometer varies from atmospheric the respective switches tilt accordingly but at different rates,—so that the mercury in one switch 128 establishes electric contact between the two wires of an electric circuit at one end of one of the tubular switches before the mercury of the other switch similarly functions.

The pairs of wires 129, 131, 133 and 135 are in electric circuits with solenoids similar to those already described.

In Figs. 4 to 6 is illustrated a form of diffusion cell in which the inner or pressure-developing chamber 56 is divided into a plurality of separate cells by the partition members 130. These members as shown extend from the outer wall of the cell 32 to the wall of tube 62; or they may extend from the outer cell wall to the casing 54. The chamber 56 is thereby divided into a number of spaces of equal volume 156, each being adapted to be separately and successively connected with the manometer tube 64. The construction is such as to prevent the escape of pressure developed in one space 156 into any of the other spaces.

In this modification, the tube 62 is in the form of a hollow sleeve valve 162 rotatable in an outer fixed valve tube 164, the latter of which is in communication at its lower ends with the manometer 64. A slot 166 in the upper end of valve 162 is adapted to successively register with each of a number of slots in the tube 164, each leading to one of the respective spaces 156 for connecting each of the latter in turn with the manometer. A shaft 167 at the lower end of the rotary member 162 has mounted thereon cams 168 and 170, adapted successively to contact with yielding valves on the respective outlet lines 66, and on the combustion gas inlet lines to the chambers 50. A cam 174 on an extension of member 162 coacts successively with yielding valves on air lines leading from a leader 175 to each inner space 156 opposite the outlet lines 66. Gas inlets 157 and gas outlets 159 to the respective outer chambers 50 are so connected respectively with the conduits 34 and 36 that while the gas mixture being tested is being passed through one of the compartments 50, it is cut off from the others. Alternatively a number of single diffusion cell units may be operatively interconnected in any other suitable manner to function in the manner indicated.

By so designing the diffusion cell as to provide an inner pressure chamber of small volume and one which is under the pressure effect of gas diffusing through a porous diaphragm of very extensive diffusion surface, this type of diffusion device has been successfully adapted for the control of a combustion operation where a quick response to changes in conditions within the combustion zone is necessitated. It is possible to build up sufficient pressure rapidly so as to make successive determinations at spaced intervals of from 30 seconds to 1½ minutes or more. The time occupied by each successive diffusion period and the other conditions of each successive test are identical, and therefore very satisfactory comparative results are obtained, which are effectively utilized for combustion control in the manner described.

If desired, the gas to be examined may flow through the system including the diffusion cell 32 under uniform positive pressure continuously maintained by a suitable pump or fan disposed in the conduit 20 leading from the combustion

chamber. As shown in Fig. 1, a blower 21 may draw a sample of gases through a sampling line 23 and force the same at a regulated rate and pressure through a valve-controlled conduit 25 to the line 20 leading to the dry filter.

In the practice of the invention, utilizing apparatus of the type shown in Fig. 1, a current of exhaust gases is drawn from the combustion chamber through conduit 20 and is passed successively through the filter 22 and cooler 26 to the valve 28. Thus any foreign matter and moisture is removed from the gases. The inner member 30 of the valve is continuously rotated under the action of a constant speed motor or the like whereby intermittently for definite periods of time, the gases flow into and through the outer chamber 50 of the diffusion cell and thence out through conduit 36, valve 28 and conduit 38 to a point of discharge. During this period of operation the lighter gravity reducing constituents such as hydrogen and carbon monoxide present in the gases tend to diffuse through the porous diaphragm to the small inner chamber 56 more rapidly than the components of the air in the latter diffuse outwardly therefrom. There thus results a rapid increase of pressure in the inner vessel and in the small or capillary manometer tube 64 connected therewith. The floating electric contact 78 rides upon the top of the liquid in the manometer tube and as it reaches the level of each pair of contacts it is adapted, when contacts 100, 100 are interconnected, to close the electric circuit and energize a corresponding solenoid. As the inner member 30 of the valve controlling the flow of gases to the diffusion cell continues to rotate, the flow of gas to the diffusion cell 32 is cut off for a predetermined period. Just prior to the resumption of gaseous flow through line 24 to the cell 32, the pressure developed in the inner chamber 56 is released by a yielding valve in line 66 which is periodically operated by a cam mounted on a shaft 180 interconnected by gearing (not shown) with the mechanism rotating the inner valve member 30.

15 The arrangement of parts controlling the operation of rotary member 30 and the valves in conduits 66 is such that just prior to the release of pressure in the inner chamber 56 the main electric circuit is closed through the connector 50 102 in the rotating member 30. Thereupon a current flows through that pair of contactor members temporarily connected at the moment by the floating contactor 78. The solenoid in such circuit is then energized, either to open or 55 to close a needle valve controlling the flow of fuel to the furnace, or to modify the volume of air flowing to the furnace from fan 16. A moment later the circuit is again broken at the rotary member 30, and the valves 67 are closed.

60 The solenoid-operated valves are so constructed that they hold their adjustment when the solenoids operating them are de-energized.

65 The fluid in the manometer tube may be an electric conductor such as mercury instead of the non-conductor described above. In such instance the contacts in the manometer tube are so disposed that the current flowing in this case through the mercury of the manometer, when the main electric circuit momentarily is closed, successively energizes the solenoids to open or 70 close one fuel valve after the other as needed. The electric contacts 68 are located in the other leg of the manometer tube in this modification. One lead wire connects with the mercury at the 75 lowermost point in the manometer.

Various other means than those shown may be employed for causing electric current to flow through the circuit at predetermined regular intervals, for the purpose stated.

80 In instances where the control of combustion within an internal combustion motor is desired, the construction of the burner 14, fan 16 and associated parts may be modified in suitable manner to provide for carburetion,—the usual air inlet and Venturi orifice being provided in line 12 between the valve 84 and the motor. The motor 18 under the control of the solenoid 98 may then be employed for operating a butterfly valve in the air inlet line.

85 While air is the gas generally employed as the standard gas within the inner chamber 56 when beginning the diffusion operation upon a gas being examined, it is within the scope of the present invention to employ in place thereof, hydrogen, helium or other gases having a low specific gravity and a high rate of diffusibility,—or a high gravity gas such as carbon dioxide.

90 The invention is susceptible of modification within the scope of the appended claims.

I claim:

100 1. In a porous diaphragm gas analyzer containing an analyzer cell, automatic intermittently operating means for periodically purging the analyzer cell, and automatic means for regulating analyzing periods.

105 2. In a porous diaphragm gas analyzer, an analyzer cell, means for intermittently at pre-selected intervals modifying the pressure existing within the said cell, means for intermittently returning the pressure within the cell to a pre-selected standard, and automatic means responsive to the pressure within the cell at successive pre-selected periods and adapted to adjust the flow of an element of combustion to a combustion chamber.

110 3. Apparatus for controlling a combustion operation which comprises means, including a porous diaphragm, responsive to the reducing constituents in a gas mixture and tending to maintain the reducing constituents in such mixture at a constant minimum value, and periodically-functioning means responsive when so functioning to a departure of the said reducing constituents from the said minimum value for progressively adjusting the first-named means to restore the reducing constituents to the said minimum value.

115 4. Automatic means for controlling the flow of an element of combustion to a combustion chamber, which comprises in combination a cell, a porous diaphragm within the cell and adapted to divide the interior thereof into two gas chambers, means for flowing a fluid mixture through one of said chambers, pressure-responsive means operatively associated with the other of said chambers, means for controlledly connecting the last named chamber with the atmosphere for displacing the gas in such chamber, a conduit leading to a combustion zone and adapted to conduct thereto an element of combustion, and means controlled by the said pressure-responsive means adapted to regulate the flow of the said element of combustion through the conduit.

120 5. Automatic means for controlling the flow of an element of combustion to a combustion zone, which comprises in combination a cell, a porous diaphragm within the cell and adapted to divide the interior thereof into two gas chambers, means for flowing a fluid mixture through one of said chambers, pressure responsive means operative-

- ly associated with the other of said chambers, means for controlledly connecting the last named chamber with a source of fluid of known composition, a conduit leading to a combustion zone 5 and adapted to introduce thereto a fluid element of combustion, and means including an electric circuit controlled by the said pressure responsive means for regulating the flow of the said element of combustion through the said conduit.
- 10 6. Automatic means for controlling the efficiency of a combustion operation which comprises in combination a cell, a porous diaphragm associated with the cell and adapted to divide the interior thereof into two gas chambers, means for withdrawing exhaust gases from a combustion chamber and for filtering the same and cooling them to a preselected temperature, means for introducing the filtered and cooled gases into one of the said gas chambers, pressure responsive means operatively associated with the other of said gas chambers, a conduit connected with the combustion chamber and adapted to conduct an element of combustion thereto, and means controlled by the said pressure responsive means for regulating the flow of the element of combustion through the conduit, the said diaphragm and cell being of such shape and size as to provide in the cell a very large diaphragm diffusion surface and a very small gas space in the last-named gas chamber. 30
7. Automatic means for controlling the flow of an element of combustion to a combustion chamber which comprises in combination a cell, a gas impermeable member within the cell, a porous diaphragm within the cell and surrounding and closely adjacent to the last-named member and defining therebetween an inner gas chamber of small volume, and defining with the cell walls an outer chamber, and means for flowing a fluid mixture to be tested through the said outer chamber in contact with the said diaphragm, pressure responsive means operatively associated with the said inner chamber of small volume, means for controlledly connecting the last-named chamber with a source of fluid of known composition for displacing the gases present in the said chamber, a conduit leading to a combustion chamber and adapted to convey thereto at least one fluid element of combustion, and means controlled by the said pressure responsive means for regulating the flow of fluid through the said conduit. 45
8. Automatic mechanism for controlling the efficiency of a combustion operation which comprises means for withdrawing exhaust gases from such combustion operation, means for cleaning and cooling such gases, and for removing condensed moisture therefrom, means for passing the cleaned and cooled gases under controlled conditions of pressure into contact with a gas permeable diaphragm separating two gas zones, pressure responsive means operatively associated with one of the said gas zones, means including an electric circuit controlled by the said pressure responsive means for regulating the flow of combustion supporting gas to the combustion zone, means for periodically discontinuing the flow of exhaust gases in contact with the said diaphragm and for releasing the pressure on the gas zone associated with the pressure responsive means, and means for closing the said electric circuit for a short period immediately prior to the said release of pressure. 60
9. Mechanism for regulating the flow of an element of combustion to a combustion chamber, which comprises a chamber, a porous diaphragm of irregular annular shape within said chamber, a gas impermeable member within the annular porous diaphragm and closely adjacent its inner wall and defining therewith a second gas chamber of small capacity, means for flowing a fluid mixture containing combustible gases through the outer of said chambers, pressure responsive means operatively associated with the said second chamber and including a fluid-operated electric switch, said switch being in a normally open electric circuit adapted respectively to control the flow of air and fuel to the combustion chamber, means for periodically discontinuing the flow of gas through the outer chamber, and means associated with the last named means for periodically closing the said electric circuit. 80
10. The method of controlling a combustion operation which comprises cleaning and cooling exhaust gases from a combustion operation, bringing the gases into contact for a preselected period of time with a porous diaphragm surrounding a gas-tight space, and utilizing the pressure condition in the said space at the end of the said period of time for adjusting the flow of an element of combustion to the said combustion operation. 95
11. A gas analyzing method, comprising withdrawing waste gases from a combustion operation, filtering the same and cooling them to a uniform regulated temperature, diffusing the filtered and cooled gases through a porous diaphragm into a small enclosed space containing a control gas, intermittently measuring the resultant gas pressure within the said enclosed space and subsequently releasing the pressure within the enclosed space and purging the diffused gases from the latter with the said control gas. 105
12. A gas analyzing method, comprising withdrawing waste gases from a combustion operation, filtering the same and diffusing the filtered gases through a porous diaphragm into a small enclosed space containing a control gas, intermittently measuring the resultant gas pressure within the said enclosed space, and thereafter purging the diffused gases from the latter. 115
13. In a porous diaphragm gas analyzer, in combination a cell, a porous diaphragm within the cell and adapted to divide the interior thereof into two gas-tight chambers, means for flowing a fluid mixture at a regulated rate through one of the said chambers, calibrated pressure-responsive means operatively connected with the other of the said chambers, automatic means for controlledly connecting the last-named chamber with the atmosphere at spaced intervals and for displacing the gas in that chamber, and automatic means adapted periodically to fill the last-named chamber with a standard gas. 125
14. In a porous diaphragm gas analyzer, a gas tight analyzer cell divided into a large compartment and a small compartment by a porous diaphragm having a large surface area, means adapted to conduct filtered combustion gases through the said large compartment, means for interrupting the said gas flow at regulated intervals, means responsive to the pressure in the other of said compartments, means controlled by the said pressure-responsive means and adapted when energized to adjust the flow of an element of combustion to a combustion chamber, and automatic mechanism for periodically energizing the last-named means. 135
15. In a porous diaphragm gas analyzer, an analyzer cell divided into a large compartment and a small compartment by a porous diaphragm

having a large surface area, means adapted to conduct filtered combustion gases through the said large compartment, automatic means for interrupting the said gas flow at regulated intervals, means responsive to the pressure in the said small compartment, means controlled by the said pressure responsive means and adapted when energized to adjust the flow of an element

of combustion to a combustion chamber, automatic mechanism for periodically energizing the last-named means, and means associated with the small compartment for periodically purging the latter of combustion gas components by means of a standard gas.
